MAX SCHLING, OF NEW YORK, N. Y.

WINDOW GUARD.

Application filed April 29, 1925, Serial No. 26,611. Renewed April 20, 1926.

The object of this invention is to provide a guard for window openings which shall be adjustable and removable, strong and reliable, and simple in construction and operation. The guard has side members, extensible cross-bars, screw means for thrusting the sides of the guard apart to seat it solidly in the window guides, and for permitting the guard to be readily collapsed for removal, and means for locking the members when seated in window openings of different widths.

In the accompanying drawings forming part hereof:

15 Fig. 1 is an elevation of the window guard in a window, the sides of the window frame being indicated in section;

20 Fig. 2 is a view on a larger scale in transverse vertical section on the line 2—2 of Fig. 1; and

Fig. 3 is a longitudinal section on a still larger scale showing the clamping and locking means.

The guard comprises two vertical side members 2, 3 adapted to stand in the guides of a window beneath the raised sash α . Between these members there is a set of extensible cross-bars, preferably three in number, though this might be varied.

30 The upper and lower cross-bars in the illustrated form are alike in construction, and are marked 4. The middle cross-bar has the screw means, and is marked 5.

Each of the cross-bars 4 consist of a stout tube 6 connected to the side piece 2, and plain rods 7 connected to the side piece 3 and slidably in and out in the tubes. The cross-bar 5 likewise comprises a tube 8 and a rod 9 connected to the respective side pieces, but the rod 9 for a considerable part of its length is formed with a screw-thread 10 and with a longitudinal groove 11.

A nut or female screw member 12 is placed on the screw 10 to bear against the end of the tube 8 as an abutment. This nut member 45 is of substantial length and diameter, and is knurled, to form a good hand grip so that the nut may be turned powerfully to force the two sides of the guard apart. In this way the side members 2, 3 are jammed 50 against the sides of the window frame, holding the structure rigid, and calling for more effort than a small child can exert to release the guard by turning the nut in the reverse direction. A set-screw 13 is threaded 55 through a boss 14 on the tube 8, near the nut. This screw enters the groove 11 of the screw-threaded rod and keeps the same from turning, and when set by a screw driver hard against the rod locks the parts even should 60 the nut 12 become loosened in some manner.

While the preferred form of the invention has been described in detail, the invention is not necessarily limited to such form, since there may be changes in details of substitutions of equivalents within the scope of 65 the claim.

What is claimed as new is:

A window guard comprising vertical side pieces, a plurality of extensible cross-bars 70 between said side pieces, one of said cross-bars consisting of a tube connected to one of the side pieces and a screw-threaded rod connected to the other side piece and entering said tube, a thrust nut on said rod to bear 75 against the end of said tube, said screw-threaded rod having a longitudinal groove, and a set-screw carried by the tube to lock the parts independently of said nut, said set-screw likewise cooperating with said 80 groove to hold the parts against relative turning.

MAX SCHLING.
